UNITED STATES PATENT OFFICE

149,350

DESIGN FOR A TOASTER

Lurelle Guild, Noroton, Conn., assignor to Westinghouse Electric Corporation, a corporation of Pennsylvania

Application January 23, 1947, Serial No. 136,315

Term of patent 14 years

(Cl. D81—10)

To all whom it may concern:

Be it known that I, Lurelle Guild, a citizen of the United States, residing at Noroton, in the county of Fairfield and State of Connecticut, have invented a new, original, and ornamental Design for Toaster, of which the following is a specification, reference being had to the accompanying drawing, forming a part thereof.

Fig. 1 is a perspective view showing the top, end and one side of a toaster embodying my new design;

Fig. 2 is an elevational view of the side opposite that shown in Fig. 1;

Fig. 3 is a fragmentary plan view of the base portion taken on line III—III of Fig. 2; and

Fig. 4 is a fragmentary sectional view taken on line IV—IV of Fig. 2.

The dominant features of my design reside in the portions shown in full lines.

I claim:

The ornamental design for a toaster, substantially as shown and described.

LURELLE GUILD.
